(57) **CLAIM**

The ornamental design of a door frame mounted massager, as shown and described.

DESCRIPTION

FIG. 1 is a front view of a door frame mounted massager showing the new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a rear perspective view thereof.

The broken lines shown in the figures are for the purpose of illustrating portions of the door frame mounted massager and form no part of the claimed design.

1 Claim, 6 Drawing Sheets(56)
